UNITED STATES PATENT OFFICE.

ALBERT WEISS, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 17,904, dated November 22, 1867.

Application filed October 22, 1867. Serial No. 253,147. Term of patent 3½ years.

To all whom it may concern:

Be it known that I, ALBERT WEISS, a subject of the Emperor of Germany, residing at Philadelphia, in the county of Philadelphia and State of Pennsylvania, have invented and produced a new and original Design for a Rug, of which the following is a specification, reference being had to the accompanying photographic print, forming a part thereof, which conveys to any one skilled in the art of rug-weaving a clear understanding of the same, and is sufficient to enable such person to use my invention.

What I claim as my invention, and desire to secure by Letters Patent, is—

The design for a rug, consisting of the ornamentalations shown in the photographic print accompanying this specification.

ALBERT WEISS.
